United States Patent

Des. 240,985
Patented Aug. 17, 1976

240,985

DISPLAY UNIT

Gerald W. Damsky, Merrick, Lawrence Feldman, Long Beach, and James Edward Rohr, Medford, N.Y., assignors to Ev.Game Inc., Freeport, N.Y.

Filed Sept. 23, 1974, Ser. No. 508,657

Term of patent 14 years

Int. Cl. D20—02

U.S. Cl. D6—85

The sole figure is a perspective view of a display unit showing our new design.

The side which is not shown is a mirror image of that which is shown.

The rear is partially open and unornamented.

We claim:

The ornamental design for a display unit, as shown.
